US00D994876S

(12) **United States Design Patent** (10) Patent No.: **US D994,876 S**
Bornholdt et al. (45) Date of Patent: ** Aug. 8, 2023

(54) **CUSHION ASSEMBLY FOR BREATHING
MASK ASSEMBLY**

(56)

CLAIM

The ornamental design for a cushion assembly for breathing mask assembly, as shown and described.

DESCRIPTION

FIG. 1 is a front, top, and left-side perspective view of a cushion assembly for breathing mask assembly embodying our new design;

FIG. 2 is a rear, top, and right-side perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a bottom view thereof.

Broken lines are used to illustrate portions of the cushion assembly for breathing mask assembly that form no part of the claimed design.
